UNITED STATES PATENT OFFICE

2,116,453

SIZING DEVICE FOR WINDING MACHINES

George N. Taylor, East Providence, R. I., assignor
to Universal Winding Company, Boston, Mass.,
a corporation of Massachusetts

Application November 17, 1936, Serial No. 111,296

15 Claims. (Cl. 242—39)

This invention relates to winding machines and more particularly to an improved sizing device for arresting the operation of the machine when the package being wound reaches a predetermined size.

In the present specification and claims the term "package" is used in a general sense to indicate any form of wound mass and the term "yarn" is intended to designate any kind of strand material whether textile or otherwise.

One object of the present invention is to provide a sizing device for controlling the stopping mechanism of the machine to cause it to act with promptness and precision to arrest the winding when the package reaches a predetermined size.

Another object of the invention is to provide a device of the type indicated actuated by the movement of the thread-guide away from the axis of the package being wound to initiate the operation of the stopping mechanism of the winding machine without causing undue pressure of the guide against the package.

Another object of the invention is to provide a device of the type indicated having a micrometer adjustment for setting it to accurately control the size of the package being wound.

Another object of the invention is to provide a device of the type indicated in the form of an attachment which can be applied to machines now in use without altering the structure thereof.

Further objects of the improvement are set forth in the following specification which describes a preferred embodiment of the invention, by way of example only, as illustrated by the accompanying drawings. In the drawings:

Fig. 1 is a side elevational view of a conventional type of winding machine showing the present invention applied thereto and illustrating the parts of the machine in position when the package is only partially wound;

Fig. 2 is a similar view showing the parts of the machine moved to position as the package reaches its predetermined size and illustrating the manner in which the action of the sizing device is initiated;

Fig. 3 is a similar view showing the sizing device in position at the completion of the actuation of the winding machine stopping mechanism which arrests the winding operation;

Fig. 4 is an enlarged detailed view of the sizing device shown in connection with the essential parts of the winding machine with which it operates;

Fig. 5 is an enlarged sectional view on line 5—5 of Fig. 4;

Fig. 6 is a detailed view of the micrometer adjusting means for the sizing device;

Fig. 7 is a composite view in perspective of the several parts of the sizing device showing them in disassembled relationship;

Fig. 8 is a view in reduced scale of the stopping mechanism of the winding machine illustrating the clutch device in vertical section; and

Fig. 9 is an end view of the clutch throw-out mechanism part-sectional on line 9—9 of Fig. 8 looking in the direction indicated by the arrow.

In the present specification and drawings the invention is described and illustrated as applied to use with a conventional type of winding machine having a positively driven spindle on which the package is wound. It is to be noted, however, that the improved device may be adapted for use with other types of winding machines and therefore the invention is not limited in its mode of application.

In machines of the present type it is common to provide means for arresting the winding operation when the package reaches a predetermined size, such means being usually actuated by the movement of the thread-guide away from the axis of the winding-spindle as caused by the increase in diameter of the package. The thread-guide is usually mounted on a pivoted frame which is counterweighted to hold the guide in close contact with the winding and in previously-used stopping devices wedges or like means are engaged by the guide-supporting frame as the package reaches the desired size with the wedging action operating to release the detent-means which normally hold the stopping mechanism inoperative with power applied to drive the machine. Under present day practice it is desirable for certain purposes, for example, in producing cops for dyeing, to wind the packages "soft", that is under light tension and pressure so that the yarn mass will be porous for the penetration of the dye thereto.

For this method of winding it is essential that the thread-guide shall bear against the package with only a light pressure and it has been found that with the usual sizing device the force required to release the detents to actuate the stopping mechanism causes a considerable pressure to be exerted on the guide and by the guide against the package. As a result the mass of yarn in the package is liable to be crushed and the whole package distorted, frequently causing bulging at its ends and displacement of the coils of yarn therein which prevents free delivery of the material in unwinding. To obviate this difficulty and

overcome the disadvantages of previously used sizing devices the present invention contemplates the employment of a knock-off member which is displaced in position by a light, gentle contact of the guide-carrying frame therewith to cause it to be actuated by a going element of the machine to positively release the detents whereby to initiate the functioning of the stopping mechanism. With the present device, practically no pressure is applied to the thread-guide during the actuation of the stopping mechanism and therefore soft packages may be wound without danger of crushing or distorting the yarn mass therein.

Referring now to the drawings, the machine herein described and illustrated comprises a box-like frame 2 having bearings for mounting a horizontal winding-spindle 5 on which the package is wound. Journaled in bearings below the winding-spindle 5 is a cam-shaft 6 carrying a helical cam, not herein shown, for reciprocating the thread-guide 10 which traverses the yarn on the package. Pivoted on the cam-shaft 6 is a traverse-frame 8 which supports the thread-guide 10 to adapt it to reciprocate longitudinally of the winding-spindle 5 and to move away therefrom with the growth of the package as it is wound on the spindle. The thread-guide 10 is fast at the end of a traverse-bar or rod 11 which slides in grooves 12 extending longitudinally of the traverse-frame 8, and rising from the traverse-frame is a backing plate 13 along which the guide slides during its reciprocatory motion.

The traverse-frame 8 carries a thread-ball 14 across which the yarn y leads as it feeds through a notch or slot in the thread-guide 10, by which it is traversed from end to end of the package being wound. A tension-device, indicated at 1 in Fig. 1, is usually provided for applying resistance to the draft of the yarn as it feeds from its supply to the thread-guide 10 to be dispersed thereby in layers which build up the package on the winding-spindle 5. The machine may be driven from any suitable source of power by a belt, gearing or other means and, as herein shown, power is applied to the winding-spindle 5 through a driving pulley 15 and clutch 16 illustrated in Fig. 8 of the drawings. A belt 17 connects the driving pulley 15 with a motor or other suitable prime-mover to transmit power to the machine. The clutch 16 is fast on the rearward end of the winding-spindle 5 and the driving pulley 15 is slidably engaged therewith to operate the machine, or released therefrom to arrest the winding operation, by means as next described.

Supported in bearings at the top of the machine frame 2 is a horizontal rod or rocker-shaft 20, on the forward end of which is fixedly mounted a starting handle or lever 21. Fast on the rearward end of the rod 20 is a two-armed lever 22, shown in detail in Fig. 9, adapted to cooperate with a tapered flange 23 on the end of the hub 24 of the driving pulley 15 to shift the pulley longitudinally of its axis. One arm 25 of the two-armed lever 22 has a beveled face adapted to engage the beveled side of the flange 23 to slide the driving pulley 15 into engagement with the clutch 16; while the second arm 26 has a similar beveled end adapted to engage the opposite beveled side of the flange 23 to withdraw the driving pulley 15 from engagement with the clutch 16. The hub 24 of the pulley 15 slides on a sleeve or bushing 27 which is free to rotate on the spindle 5, the pulley being keyed to the sleeve by a pin-

and-slot connection indicated by dotted lines at 28.

A pair of radially-extending spring-arms 29 secured to the web of the pulley 15 are arranged with their angularly-bent ends adapted to slide over beveled faces 30 at one end of the sleeve 27. These spring-arms 29 have the effect to urge the pulley 15 into engagement with the clutch 16 to release its flange 23 from engagement with the arm 26 of the lever 22 whereby to prevent frictional contact between these parts during the rotation of the driving pulley. The construction and method of operation of the present clutch-device are the same as shown and described in United States Letters Patent No. 834,778 of October 30, 1906, and will therefore not be described more specifically herein. Suffice it to state that as the lever 22 is rocked by the rod 20 in a clockwise direction, as viewed in Fig. 9, its arm 25 will cause the pulley 15 to be engaged with the clutch 16 to drive the spindle 5; whereas, when the lever 22 is rocked in the opposite direction its arm 26 will act to withdraw the pulley from engagement with the clutch 16 to release the drive and arrest the operation of the machine.

A helical spring 31 connected to the arm 26 of the lever 22 and anchored at 32 to a part of the machine frame 2 tends to rock the lever to withdraw the pulley from engagement with the clutch 16; the lever 22 being rocked in the opposite direction to connect the drive to start the operation of the machine by means of the handle or starting lever 21 on the rod 20. The rod 20 and lever 22 are normally maintained in position with the driving pulley 15 engaged with the clutch 16 under the control of a pair of detents shown in Figs. 1, 2 and 3 of the drawings. A sickle-shaped arm 35 reaches downwardly from the starting lever 21 and is formed at its end with a shouldered detent 36 adapted to engage a notched detent-shoulder 37 on the upper arm 38 of a pivoted quadrant-shaped lever 40. The lever 40 is pivoted at 41 to the side of the machine frame 2 and its arcuately-shaped portion 42 normally extends in concentric relation to the cam-shaft 6. The under side of the quadrant 42 of the lever 40 is formed with a tapered groove 43, see Fig. 5, which is engaged by the end of a dogging lever 45 pivoted to the traverse-frame 8. The dogging lever 45 acts to resist the return of the traverse-frame toward the winding-spindle 5 after the guide 10 has been forced outwardly therefrom by the growing package, this being a usual form of construction in machines of the present type. A finger-lever 46 connected to the dogging lever 45 may be employed to manually release the latter to permit placing the thread-guide against the core of the package to start the winding operation.

To effect prompt stopping of the machine a brake-disk 47, indicated by dotted lines in Figs. 1 to 3, is usually provided on the spindle 5, being adapted to be engaged by a brake-shoe 48 carried by an arm 51 of the starting lever 21. It will be understood that the cam-shaft 6 is driven from the winding-spindle 5 through the means of gearing or a suitable belt, in accordance with the usual construction, and the elements of the machine as above-described are illustrated and described with greater particularity in United States Letters Patent No. 801,941 of October 17, 1905. In this prior patent the means for arresting the operation of the machine when the package reaches a predetermined size consists in a wedge-block or member 49 adjustable along the 75

quadrant 42 of the lever 40 and having a beveled portion adapted to be engaged by a shoulder or ledge 9 on the traverse-frame 8 to lift the outer end of the lever 40 to release the detents 36 and 37. 5 As before indicated, such a wedging engagement between the traverse-frame 8 and the wedge-block or element 49 has the effect to resist continued movement of the thread-guide away from the axis of the package and thereby causes the 10 guide to exert an abnormal pressure against the package.

The present invention avoids the use of the above-described wedging means by employing a relatively light, pendant, knock-off member, indicated generally by the numeral 55, which is rocked by the traverse-frame 8 to cause it to engage a going part of the machine to positively lift the lever 40 to release the detents. For the sake of simplicity and to adapt the present device 20 for general application to winding machines in use without alteration in the structure thereof, the standard wedge-element 49 is utilized as an adjustable mounting for the pendant knock-off member 55. As shown in Fig. 5, the element 49 is preferably constructed of sheet-metal or bar-stock bent at right-angles to overlie the top of the quadrant 42 and looped around thereinunder with an upwardly-extending portion engaging in the groove 43 of the quadrant. A set-screw 50 25 threaded through the upper portion of the member 49 is adapted to be set up against the top of the quadrant 42 to hold the member in adjusted position thereon.

Referring more particularly to Figs. 4 and 7 35 of the present drawings, the member 55 is preferably made in two parts which are adjustable in relation to each other for a purpose later explained. Its main portion consists of a lever-arm 56 having an offset portion at its upper end 40 formed with a hole 57 for mounting it on a pivot-stud or bearing hub 58. The hub 58 projects from the side of a disk 59 in eccentric relation to the axis thereof and has a bore 60 which is centered axially of the disk. The hub 58 passes through 45 the hole 57 in the lever-arm 56 and is held with its end abutting the side of the element 49 by means of a screw 61 inserted through its bore 60 and screwed into said element, see Fig. 5. By releasing the screw 61 the disk 59 may be turned 50 thereon to vary the position of the axis of the eccentric hub 58 on which the lever-arm 56 rocks; it being noted that the periphery of the disk 59 is knurled to facilitate this manual adjustment. The depending portion of the lever-arm 56 is twisted at 63 to position its lower end at right-angles to its main portion and extending laterally from this end of the arm is a projection 64 which serves merely as a weight to counter-balance the member in its suspension. Projecting 55 forwardly from the hole 57 in the member 56 is an arm 65 having a lug 66 bent at right-angles thereto and formed at its end with a laterally-extending slot 67 which serves as the means for connecting the lever-arm 56 with its companion member.

The companion member associated with the member 56 is in the form of a cross-arm 70 having its central portion provided with a hole 71 60 corresponding to the hole 57 in the lever-arm 56 to adapt it to be arranged alongside of the latter and pivoted therewith on the hub 58 of the disk 59. At the forward side of the hole 71 the arm 70 is formed with a laterally-extending lug 72 65 bent at right-angles thereto and adapted to un-

derlie the slotted lug 66 on the lever-arm 56. A screw 75 having a knurled head 76 reaches down through the slot 67 in the lug 66 with its threaded end screwed into a tapped hole 73 in the lug 72 and projecting therefrom to receive a check-nut 77. Surrounding the screw 75 and held under tension between the two lugs 66 and 72 is a helical spring 78, the upper end of which bears against a washer 79. With the two parts of the member 55, that is the lever-arm 56 and the cross-arm 70, pivoted on the hub 58 as shown in Figs. 4 and 5 the screw 75 may be adjusted to vary the distance between the lugs 66 and 72 whereby to adjust the position of the arm 70 with respect to the lever-arm 56; after which the nut 77 is tightened to lock the parts in fixed relationship. The arm 70 is formed on the under side of its rearward end with an arcuately shaped cam-face or edge 80 adapted to be engaged by the shoulder 9 on the traverse-frame 8 as the latter swings outwardly with the growth in the winding. The arm 70 is slotted at 81 and the slotted portion of the metal bent to one side to form a stop 82 which engages against the edge of the member 49 to locate the arm with its cam-face 80 in position to be engaged by the shoulder 9 on the traverse-frame 8. The lever-arm 56 of the member 55 is thus supported in angular position extending downwardly and rearwardly towards the cam-shaft 6. 30

Mounted fast on the outer end of the cam-shaft 6 is a going member illustrated in the form of a disk or wheel 83 having its periphery serrated or formed with teeth or cogs 84 projecting therefrom. The wheel 83 is a standard part of the 35 winding machine, being provided for the purpose of engaging a stop-lever or drop-wire 85 pivoted to the end of the quadrant 42 of the lever 40 and normally suspended by the strand of yarn y feeding from the tension-device 7 to the thread-guide 10. When the yarn breaks, or its supply is exhausted, the drop-wire 85 is tilted by the action of gravity to cause its inner end to engage the periphery of the wheel 83. The wheel 83 rotates in the direction indicated by the arrow in Fig. 1, 45 and when the drop-wire 85 is engaged therewith it will rock the lever 40 upward to release the detents 36 and 37 which maintain the driving pulley 15 in connection with the clutch 16. The present sizing device operates in somewhat the 50 same manner as next explained.

To start the machine the lever or handle 21 is rocked in a clockwise direction, as viewed in Fig. 1, to cause the lever 22, see Figs. 8 and 9, to shift the driving pulley 15 into engagement with 55 the clutch 16; the arm 35 of the lever 21 being thereby rocked downwardly to engage its detent-shoulder 36 with the detent 37 on the quadrant lever 40 to maintain the stopping mechanism inactive. During the operation of the machine 60 the yarn y feeds upwardly across the thread-bail 14 and through the slot or notch in the thread-guide 10 which is reciprocated longitudinally of the spindle 5 to traverse the yarn on the package. The cop or package C is usually wound on 65 a fiber or paper tube t secured to the spindle 5 and as the layers of winding are deposited in place the thread-guide 10 is caused to recede from the spindle with the traverse-frame 8 rocking on its pivot on the cam-shaft 6. The 70 traverse-frame 8 is balanced by a counter-weight 18, see Fig. 1, and in some cases by other means, to apply a light pressure to the thread-guide 10 to maintain it in contact with the surface of the package C and during the 75

receding movement of the guide from the spindle 5 during the growth of the package the traverse-frame is prevented from jumping or vibrating by the action of the dogging lever 45 in the usual 5 manner as well understood by those versed in the art.

The sizing device forming the subject-matter of the present invention is adjusted to adapt it to be actuated immediately the thread-guide 10 has 10 moved away from the winding-spindle 5 a distance corresponding to the desired size of the package, that is, its radial dimension. For an initial, approximate adjustment of the pendant member 55 on the lever 40 the traverse-frame 8 is 15 swung outwardly to place the thread-guide 10 in a position corresponding to that which it will assume just before the package reaches the desired size. The element 49 is then slid along the quadrant 42 of the lever 40 to locate the member 20 55 in such position that the cam-face or edge 80 on the arm 70 is engaged with the shoulder 9 on the traverse-frame 8 so that further movement of the traverse-frame will act to rock the arm 70 upwardly; the element 49 being then fixed 25 in position by tightening the set-screw 50, see Fig. 5. The screw 51 is next loosened and the disk 58 rotated thereon to adjust the effective length of the lever-arm 56 of the member 55 to compensate for inaccuracies in manufacture of 30 the parts of the device. This adjustment serves to position the lower end of the lever-arm 56 in proper relation to the periphery of the knock-off wheel 83 to insure that when the lever engages the wheel it will not ride up onto the top of the 35 wheel and remain suspended thereby to prevent it from swinging back under the action of gravity. This adjustment is important, for if the pendant member 55 is not returned to initial position after the arrestment of the winding upon 40 completion of each package it will fail to act at the completion of the next package wound on the machine.

The final micrometer adjustment of the sizing device is made with the screw 75. By tightening 45 or loosening this screw the lugs 66 and 72 on the members 55 and 70, respectively, may be drawn together or caused to be spread apart by the spring 78 whereby to locate the lower end of the lever-arm 56 in such position that it will be 50 quickly engaged by the periphery of the knock-off wheel 83 when the arm 70 is rocked upwardly by the engagement of the shoulder 9 on the traverse-frame 8 with the cam-face 80 of the arm. In other words, this last adjustment sets 55 the device for prompt action immediately the package C has reached its predetermined diameter; the traverse-frame 8 having then been caused to move outwardly to such an extent that the engagement of its shoulder 9 with the cam- 60 face 80 lifts the arm 70 to a very slight extent. It will be understood that when the end of the lever-arm 56 engages the periphery of the wheel 83 it will be caught by one of the teeth 84 thereon and thereby the arm 56 is pushed upwardly 65 to lift the quadrant 42 of the lever 40 to release the detents 36 and 37.

Upon release of the detents 36 and 37 the spring 31, see Fig. 9, is energized to rock the lever 22 to move its end 26 into engagement with the 70 beveled side of the flange 23 to withdraw the driving pulley 15 from the clutch 16. As the lever 22 is rocked under this action the rod 28 is rocked with it to cause the brake-shoe 48 to engage the disk 47 on the winding-spindle 5 to 75 insure a prompt stopping of the machine. Should

the knock-off occur too soon, however, that is before the package reaches its desired size the screw 75 may be adjusted to locate the end of the lever-arm 56 farther away from the periphery of the knock-off wheel 83. The winding operation is thus arrested immediately the package reaches its predetermined size and due to the pendant or floating suspension of the knock-off member 55 practically no pressure is applied to the thread-guide 10. In other words, the movement of the traverse-frame 8 as it engages the cam-surface on the arm 70 of the member 55 is subject to practically no resistance and consequently no pressure is applied to the thread-guide 10 to cause it to bear too heavily against the surface of the package. Stated briefly, the sizing device operates without increasing the pressure of the thread-guide against the package so that even though the latter may be soft and spongy its shape will not be distorted or the yarn 20 therein crushed and injured.

It will be observed from the foregoing that the present invention provides a novel and efficient means for arresting the operation of the winding machine when the package being wound reaches 25 a predetermined size without causing malformation of the package or injury to the material therein. The device is simple in structure, practically proof against derangement or getting out of order, and in its present form of construction 30 it provides an attachment or fitting which may be applied to machines of standard type already in use without change in the construction and arrangement of the main elements thereof.

While the present sizing device is herein shown 35 as embodied in a preferred form of construction, by way of example, it is to be understood that various modifications may be made in the structure and arrangement of its parts without departing from the spirit or scope of the present invention. Therefore, without limiting myself in this respect, I claim:

1. In a winding machine, the combination of 45 stopping mechanism therefor, a going member, a pivoted member having an arm at one side of its pivot movable into engagement with the going member to initiate the operation of the stopping mechanism and a projection at the opposite side of the pivot, and a member movable by the growth of the package being wound in direct proportion to said growth and engageable with the projection to rock the pivoted member to engage its arm with the going member.

2. In a winding machine, the combination of 55 stopping mechanism therefor, a going member, a member pivoted intermediate its ends, one end of said member being movable into engagement with the going member to initiate the operation of the stopping mechanism, and a member actuated by the growth of the package being wound 60 and directly engaging the pivoted member at one end to rock its opposite end into engagement with the going member.

3. In a winding machine, the combination of 65 stopping mechanism therefor, a going member, a pendant member movable to engage the going member to initiate the operation of the stopping mechanism, a cam operatively connected to the pendant member, and means moved by the growth of the package to engage the cam to rock 70 the pendant member to engage it with the going member.

4. In a winding machine, the combination of 75 stopping mechanism therefor, a going member, a pivoted member movable into engagement with

the going member to initiate the operation of the stopping mechanism, a cam operatively connected to the pivoted member, means for adjusting the cam in relation to the pivoted member, and means movable by the growth of the package to engage the cam to rock the pivoted member into engagement with the going member.

5. In a winding machine, the combination of stopping mechanism therefor, a rockable lever for initiating the operation of the stopping mechanism, a going member, movable means adjustable in position on the lever and adapted to engage the going member to rock the lever whereby to initiate operation of the stopping mechanism, and means controlled by the size of the package being wound for actuating the movable means to engage it with the going member.

6. In a winding machine, the combination of stopping mechanism therefor, a rockable lever for initiating the operation of the stopping mechanism, a going member, a member pendants supported on the lever and adapted to engage the going member to rock the lever whereby to initiate operation of the stopping mechanism, a cam operatively connected to the pendant member, means controlled by the size of the package for engaging the cam to rock the pendant member into engagement with the going member, said pendant member and cam being bodily adjustable to initially position the cam for engagement by the package-controlled means, and means for adjusting the relationship of the pendant member and cam.

7. In a winding machine, the combination of stopping mechanism therefor, a rotating wheel, a two-part lever having an arm extending at one side of its pivot for engaging the wheel and an arm at the opposite side of the pivot having a cam-face, means for adjusting the angular relationship of said arms, and means movable by the growth of the package for engaging the cam-face on one arm to rock the opposite arm into engagement with the wheel, said lever being actuated by the wheel to initiate the operation of the stopping mechanism.

8. In a winding machine, the combination of stopping mechanism therefor, a rockable control lever for initiating the operation of the stopping mechanism, a rotating wheel, a two-part knock-off lever having an arm adapted to engage the wheel to rock the control lever to initiate operation of the stopping mechanism and an arm provided with a cam-face, means controlled by the size of the package for engaging the cam-face on said last-named arm to rock the opposite arm of the knock-off lever into engagement with the wheel, said knock-off lever being adjustable on the control lever to vary the position of the cam-arm with respect to the package-controlled means, and a screw connecting the opposite arms of the knock-off lever for adjusting the relationship of the two parts thereof.

9. In a winding machine, the combination of means for rotating a package, a movable traverse-frame, means on the traverse-frame for guiding the yarn to traverse it on the package, said traverse-frame being moved by the growth of the package, stopping mechanism, a rockable control lever for initiating the operation of the stopping mechanism, a going member, and a knock-off lever on the control lever so constructed and arranged as to be directly engaged by the traverse frame, said knock-off lever being actuated into engagement with the going member by the engagement of the traverse-frame therewith

whereby to rock the control lever to initiate operation of the stopping mechanism.

10. In a winding machine, the combination of means for rotating a package, a pivoted traverse-frame, means on the traverse-frame for guiding the yarn to traverse it on the package, said traverse-frame being rocked on its pivot by the growth of the package, stopping mechanism, a rockable control lever for initiating the operation of the stopping mechanism, a continuously rotating wheel, a support adjustable along the control lever, a two-part knock-off lever pivotally mounted on the support, said knock-off lever having a cam on one part adapted to be engaged by the traverse-frame to swing its opposite part into engagement with the wheel to rock the control lever to initiate operation of the stopping mechanism, and means for adjusting the relationship of the two parts of the knock-off lever.

11. In a winding machine, the combination of means for rotating a package, a pivoted traverse-frame, said traverse-frame being rocked on its pivot by the growth of the package, a rotating wheel, stopping mechanism, a rockable control lever for initiating the operation of the stopping mechanism, a support adjustable along the control lever, a knock-off lever pivotally mounted on the support and having an arm for engaging the wheel and a laterally-extending lug, an arm pivotally mounted on the support, said arm having a portion adapted to be engaged by the traverse-frame and a lateral lug overlying the lug on the knock-off lever, and an adjusting screw connecting the lugs on the arm and lever for adjusting their relative position.

12. In a winding machine, the combination of stopping mechanism therefor, a rotating wheel, a rockable control lever for initiating the operation of the stopping mechanism, a support adjustable along the control lever, an eccentric pivot-stud carried by the support, a knock-off lever pivotally mounted on the eccentric stud and having a cam, and means movable by the growth of the package and adapted to engage the cam to swing the knock-off lever into engagement with the wheel to cause it to rock the control lever and initiate operation of the stopping mechanism, said eccentric pivot-stud being adapted for bodily adjusting the knock-off lever with respect to the package-controlled means.

13. In a winding machine, the combination of means for rotating a package, a pivoted traverse-frame, said traverse-frame being rocked on its pivot by the growth of the package, stopping mechanism, a rockable control lever for initiating operation of the stopping mechanism, a continuously rotating wheel, a support adjustable in position on the control lever, an adjustable eccentric stud on the support, a two-part knock-off lever pivotally mounted on the eccentric stud with one part adapted to be engaged by the traverse-frame to swing the other part into engagement with the wheel, said wheel and knock-off lever acting to rock the control lever to initiate operation of the stopping means, and means for adjusting the relationship of the two parts of the knock-off lever.

14. In a winding machine, the combination of stopping mechanism therefor, a going member, a pivoted member having an arm engageable with the going member to initiate the operation of the stopping mechanism and a second arm projecting on the opposite side of its pivot from the first arm, and a member movable during the growth of the package being wound and engage-

able with the second arm of the pivoted member to rock the latter to move its first arm into engagement with the going member.

15. In a winding machine, the combination of 5 stopping mechanism, a going member, an eccentric stud associated with the stopping mechanism, a member pivoted on said stud and engageable with the going member to initiate operation

of the stopping mechanism, and means movable during the growth of the winding and engageable with the pivoted member to move it into engagement with the going member, said eccentric stud being rotatable to bodily adjust the pivoted member in operative position. 5

GEORGE N. TAYLOR.
